UNITED STATES PATENT OFFICE.

WINTHROP L. JACOBS, OF EAST ORANGE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 14,874, dated March 11, 1884.

Application filed January 28, 1884. Term of patent 3½ years.

To all whom it may concern:

Be it known that I, WINTHROP L. JACOBS, of East Orange, New Jersey, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

The design consists of four main groups, with intervening open gem and leaf sprays. The group shown in the upper central part of the photograph consists of a central mass of open flowers and leaves, and sprays bearing flowers and leaves projecting from the central

mass. The group shown in the lower center of the photograph consists of a number of open flowers with drooping leaves. The group shown at the upper left-hand and at the right center of the photograph has several small open flowers with large open leaves below. The group shown at the left center and right upper and lower corners of the photograph is a similar flower-and-leaf mass with scattered projecting sprays. Scattered thickly between the groups are leaf-sprays and small flowers and twigs and gem-work, as clearly shown in the photograph.

I claim—

The design for a carpet, substantially as shown and described.

W. L. JACOBS.
